PENCIL SHARPENER

Martin Bersted, Oak Park, Ill.

Application December 28, 1935, Serial No. 56,415

15 Claims. (Cl. 120—95)

The present invention relates to a pencil sharpener and more particularly to a pencil sharpener utilizing a revolvable cutter and means for supporting a pencil while being sharpened, the pencil supporting means revolving with the cutter, to produce a smoother point on a pencil.

The pencil sharpeners in use at the present time, utilizing revolvable cutters, are so constructed that a pencil, while being sharpened, is gradually pushed against the cutter, during a sharpening operation, by the operator with a result that the sharpened point is sometimes roughened as a result of the cutting and improper movement of the pencil during sharpening.

15 The present invention has as an object provision of means for sharpening pencils with a cutter of rotatable type, wherein the pencil is rotated simultaneously with the cutter and in such direction as to impart a smooth finish to the sharpened 20 point.

Another object of the present invention is to provide, in a pencil sharpener, means for rotating a pencil during a sharpening operation.

A further object of the present invention is 25 to provide, in a pencil sharpener of the rotatable cutter type, means for moving the cutter towards and away from an inserted pencil.

A still further object of the present invention is to provide, in a pencil sharpener of the rotatable cutter type, a pencil receiving means for 30 clamping a pencil in position to be sharpened, and means for rotating the pencil receiving means with rotation of the cutter.

A still further object of the present invention 35 is to provide, in a pencil sharpener, an abutment against which the point of the pencil is moved when inserted, together with means for moving the cutter against the pencil to gradually taper the pencil to a point while the pencil is against 40 said stop.

For a further object the present invention has the provision, in a pencil sharpener of the rotatable cutter type, of means for supporting a pencil while being sharpened, a single hand operating 45 crank, and connections between the crank and pencil supporting means and rotatable cutter for rotating the pencil and cutter in opposite directions during a cutting operation.

The invention has also for a further object the 50 provision of manually operable means for moving the cutter towards and away from an inserted pencil.

The above, other and further objects of the 55 present invention will be apparent from the following description and accompanying drawings.

The accompanying drawings illustrate an embodiment of the present invention and the views thereof, as follows:

Figure 1 is an elevational view of a pencil sharpener constructed in accordance with the 5 principles of present invention.

Figure 2 is a top plan view of the sharpener of Figure 1.

Figure 3 is a view partially in elevation and partially in vertical section, through the 10 sharpener of Figure 1, showing the relationship of certain of the parts.

Figure 4 is a side elevational view of the sharpener of Figure 1 looking at the right hand face of the same.

15 Figure 5 is a fragmental view, partially in elevation and partially in section, immediately behind one of the side walls of the casing, and showing relationship between a pencil and the rotatable cutter when in cutting position.

Figure 6 is a horizontal sectional view taken substantially in the plane indicated by line VI—VI of Figure 5.

Figure 7 is a horizontal sectional view taken substantially in the plane indicated by line 25 VII—VII of Figure 5.

Figure 8 is a fragmental vertical sectional view taken along the line VIII—VIII of Figure 2.

Figure 9 is a horizontal sectional view taken substantially in the plane of line IX—IX of 30 Figure 8.

Figure 10 is a fragmental vertical sectional view taken in the plane indicated by line X—X of Figure 2.

The drawings will now be explained.

35 The pencil sharpener of the present invention contemplates a box-like body A which is herein illustrated as rectangular in plan and elevation. An L-shaped attaching bracket B is utilized to mount the pencil sharpener on any suitable support, such as a table, desk, window sill, or the like, in position for use.

Generally speaking, the sharpener is used in vertical position, that is, with a pencil inserted vertically through the upper end of the same.

45 The casing A in plan is U-shaped providing side walls 1, 2, and 3, a bottom 4, with a fourth wall 5 parallel to the wall 2 and extending upwardly from the bottom 4 terminating short of the upper extremities of the walls 1, 2, and 3, as best observed in Figure 3. The upper end of the sharpener structure comprises a top plate 6 with the descending wall 7 against which the wall 5 of the casing A rests, when the parts are assembled. The top plate 6 has lateral grooves 8 in which 50

inturned margins 9 and 10 formed on the upper extremities of the walls 1 and 3, lie to hold the parts in connected relation.

Integrally formed as a part of the top plate 6 and the side plate 7 is an enlargement 11 having stepped surfaces 12 and 13 on its exterior. This second portion 11 is vertically bored as at 14 with an inwardly extending annular flange 15 formed a slight distance above the plate 6, as may be observed in Figure 8. The flange 15 forms a counterbore 16 in which a spur gear 17 is rotatable. The gear 17 has rearwardly extending segmental portions 18, three in number, which are spaced one from another, radially, forming radial slots 19 between every two of the segments. The outer surfaces of these segmental portions are arcuate and are axially bored as at 20. Surrounding the segmental portions 18 is a collar 21 which has formed on its interior three wedges 22 equally spaced, circumferentially, to enter the spaces 19 between the segmental portions 18. Integrally formed with the collar 21, and extending into the interior thereof, are three lugs 23 which work within the recesses 20 of the segmental elements 18. Interposed between the lugs 23 and the gear 17, and disposed within the recesses 20, are springs 24, functioning to hold the collar 21 away from the gear 17.

Wedges 25 are inserted in spaces 20 with their inclined faces in opposition to the inclined faces of the wedges 22 formed as integral parts of the collar 21. The wedges 25 have faces 26 which, when the parts are assembled, extend axially of the segmental members 18 and provide surfaces 30 for engaging an inserted pencil C.

For retaining the collar 21, wedges 25, and springs 24 in operative and assembled relationship, a disc 27 rests against the outer ends of the wedges 25 and is provided with holes for receiving bolts 28 passed through the lugs 23 and are inserted into the top of the gear 17, as illustrated in Figure 8. The disc 27 has a centrally disposed aperture through which the pencil C passes.

Applied over the outer end of the collar 21 is an apertured, flanged cap 29 which serves to conceal the operative parts just described, and also serves the purpose of furnishing a grip for the application of the thumb or finger of the operator to depress the collar and relieve pressure against wedges 25, for the insertion or removal of a pencil. Normally the springs 24 move the collar 21 away from the gear 17 which action moves the wedges 25 inwardly towards the space for the pencil, and function to grip an inserted pencil and hold it 45 against movement in the sharpener.

Adjacent the gear 17, the inner surface of the plate or plate enlargement 11 is bored and threaded to receive the threaded end 30 of a stem 31. Next to the threaded end 30 of the pin is a portion 32 whose diameter is greater than the diameter of the threaded end 30 and less than the diameter of the balance of the pin, providing shoulders 33 and 34 on the pin.

Rotatably mounted on the intermediate portion 65 32 of the pin 31 is a double gear comprising a larger gear 35 and a smaller gear 36, which are preferably separately fashioned and then permanently connected together. When this double gear is installed, the smaller gear 36 meshes with the gear 17 heretofore described and is against the adjacent face of the enlargement 11 of the top plate of the structure.

Oscillatably mounted on the pin 31 is a sleeve 75 37 having a shoulder engageable by the shoulder 34 of the pin to hold the sleeve in endwise engage-

ment against the double gear. Formed as a part of the sleeve 37 is an annularly disposed arm 38.

A pin 39, secured in the arm 38, supports a rotatable cylindrical cutter 40 which is arranged with its axis at an angle to the pin 31 and also at an angle to the axis of the inserted pencil C. The inclination of the axis of the pin 39, and the rotatable cutter 40, is substantially coincident with the inclination of the point portion of the pencil as fashioned by the cutter 40. The arm 38 is wider than necessary to properly support the cutter and serves the purpose of a stop against which the end of the pencil abuts when the pencil is inserted in the sharpener.

The sleeve 37, and consequently the cutter 40 and arm 38 are mounted for oscillation on the pin 31. To oscillate the sleeve 37 and the cutter 40, the sleeve 37 is provided with a projecting pin 41 which lies in the path of an outturned foot 42 formed as part of a lever 43 which is pivoted at 44' to the top plate 6 of the structure. The lever 43 projects beyond the adjacent side surface of the structure where it is flattened to provide a hand hold 44, as may be observed in Figures 1 to 4 inclusive.

For maintaining the cutter 40 normally away from the cutting position, a spring 45 is, at one end, connected by means of a screw 46 to the sleeve 37 and, at its other end, to an extension 47 of the pivotal connection 44' for the lever. For limiting movement of the pin 41 in direction to move the cutter 40 away from cutting position, a stop may be provided.

For providing stop means for the lever 43, as it is swung to move the cutter 40 against an inserted pencil, and to provide adjustment to accommodate pencils of varying sizes, adjustable stop mechanism is herein illustrated. Pivoted at 49, on a pivot pin, in the present instance shown as threaded into the under surface of the top plate 40 6, is a bell crank having a short arm 56 and a long arm 57. The extremity of the short arm 56 is provided with a shoulder 58 which constitutes the stop against which the lever 43 is swung during cutting operation.

For shifting the bell crank, to vary the point of contact of the shoulder 58 by the lever 43, any suitable means may be employed. The means chosen to carry out this feature, in the present instance, comprises a pin 59 passing through a suitable opening 60 in the top plate 6. The inner end of the pin 59 is provided with a flat circular head 61, from which depends a pin or stud 62. The outer end of the pin 59 is threaded to receive knurled cap 63. The cap is threaded on to the end of the pin until sufficient friction or tension against the plate 6 is reached whereupon the cap is fastened to the pin by means of a set screw 64. This, therefore, prevents vibration of the pin and its connected stop from misplacement during the pencil sharpening operation.

The long arm 57 of the bell crank is provided with a slot 65 in which the stud 62 moves.

It will be observed that manipulation of the knurled cap 63 will cause a corresponding shifting movement of the shoulder 58 of the short arm 56 of the bell crank and thus vary the point at which the lever 43 is brought to rest, when it is swung in a direction to move the cutter 40 against an inserted pencil.

Supported in a lateral extension 48 of the plate 7 is the hub 49 of a gear 50. The gear 50 is arranged to mesh with the larger gear 35 of the double gear heretofore described. The hub 49 of the gear is suitably bushed by a bushing 51 ap-

plied as illustrated in Figure 8. A crank 52 is secured to the outer end of the hub 49 of the gear, by means of a screw 53, and a handle 54 is attached to the free end of the crank 52 rotating the gear 50 and the cutter element 40.

The cutter element 40 is, at its end adjacent the top plate 6, provided with a gear 55 which meshes with the larger gear 35 of the double gear heretofore described, for rotating the cutter 40 whenever the crank 52 is operated.

The operation of the pencil sharpener of the present invention is as follows:

A pencil, C, is inserted in the sharpener by the operator pressing the cap 29 downwardly, as observed in Figures 1, 3, 4, and 5 to release pressure against the wedges 25; whereupon a pencil, C, may be inserted and moved into the sharpener until its end strikes the arm 38. The operator then grasps the handle 44 of the lever 43 and then swings it from dotted line to full line position of Figure 6, that is, to say from left to right, as viewed in Figure 2, which movement swings the arm 38 to move the cutter 40 against the pencil, as illustrated in Figure 6. The operator then rotates the crank 52 while maintaining pressure against the handle 44 of the lever 43, until such time as the pencil is sharpened. If the pencil, inserted in the sharpener, is already pointed, then the operator may move the lever 43 until it strikes its stop 58, without damage to any of the parts or to the pencil. Rotation of the crank will rotate the cutter 40 and at the same time rotate the pencil C, which is firmly gripped by the wedges 25, with the axes of rotation in the same direction. This rotative movement brings about rotation of the surfaces of the cutter and the pencil point in opposite directions at the area of contact, so that the sharpening operation is accelerated and the wood of the pencil is smoothly removed without gouging any of the pencil.

When an unpointed pencil is to be sharpened, it is inserted in the sharpener with its end against the arm 38 and then sufficient pressure is applied against the handle 44 of the lever 43, as the skill of the operator may dictate, and the crank 52 rotated until the blunt end of the pencil is pointed whereupon the lever may be finally moved against its stop 58 and the completion of the pointing operation reached.

An advantage obtained by rotating the pencil simultaneously with the cutter is that the pointing operation is accelerated, and the point is much smoother than otherwise would be the case if the pencil were not rotated.

With rotary cutter sharpeners on the market at the present time, it is usual for the operator to hold the pencil in one hand and push it against the cutter. The amount of push of the pencil is guess work, and the result oftentimes is unsatisfactory, as the point of the lead is many times broken, and unless the hand pressure against the pencil is applied gently, the wood of the pencil is badly torn at the point.

After the pencil has been pointed, pressure against the lever 43 is released whereupon the spring 45 functions to move the cutter 40 away from the point, and the operator then depresses the cap 29 and withdraws the pencil from the apparatus.

The casing A serves as an enclosure for the mechanism described, and at the same time serves as a receptacle for the shavings created by repetitive sharpening operations. When the receptacle has been filled, it may be removed by sliding it off the top plate 6, the shavings dumped,

and the casing returned in place ready for further use. The casing A is removed from and applied to the top plate by movements to the right and left as viewed in Figures 1 and 3.

Suitably secured to the wall 11 of the top plate 6 is the standard B, by which the sharpener may be attached to a table, desk, ledge, shelf, or other support.

The parts of the pencil sharpener herein described, are in the main manufactured as die castings, so that the cost of assembly is reduced and quantity production of the parts is made possible.

The invention has been described herein more or less precisely as to details, yet it is to be understood that the invention is not to be limited thereby, as changes may be made in the arrangement and proportion of parts, and equivalents may be substituted, without departing from the spirit and scope of the invention.

The invention is claimed as follows:

1. In a pencil sharpener, a revolvable cutter, means mounting said cutter for bodily movement towards and away from a pencil with the cutter axis in the same axial relation with respect to the pencil axis, means for receiving a pencil for presenting it in cutting position, means for rotating said cutter, and means for rotating the pencil receiving means simultaneously with the rotation of the cutter.

2. In a pencil sharpener, rotatable means for receiving a pencil to be sharpened, means for clamping a pencil in said receiving means in relatively non-rotatable relation, axially elongated wedges projecting into the pencil space of said first means, means for exerting pressure against said wedges to move them radially inward, means for relieving pressure against said wedges to enable insertion and removal of a pencil, and means for rotating said pencil receiving means and cutter for sharpening purposes.

3. In a pencil sharpener of the rotatable cutter type, means for mounting the cutter for bodily moving it in an arcuate path towards and away from the pencil axis to vary the cutting effect of the cutter against an inserted pencil, and means normally maintaining said cutter moved away from cutting position.

4. In a pencil sharpener of the rotary cutter type, means for receiving a pencil to be sharpened, means mounting the cutter and supporting it for movement towards and away from an inserted pencil, and means normally maintaining said cutter moved away from cutting position, and means for moving said cutter against a pencil for sharpening it.

5. A pencil sharpener including a frame comprising a base, an upright and a horizontally extending top plate; a box like casing slidably supported on said top plate to complete the structure; means in said top plate for receiving and supporting a pencil in vertical position; means including provision for clamping an inserted pencil and holding it against movement relatively to the receiving means; a rotatable cutter supported by and below said top plate and having its axis inclined to the vertical; means mounting said cutter for swinging it toward and away from an inserted pencil; means normally maintaining said cutter swung away from cutting position; a crank supported in said upright; and gear connections between said crank, cutter, and pencil receiving means for rotating the cutter and pencil receiving means whenever the crank is actuated.

6. A pencil sharpener including a frame comprising a base, an upright and a horizontally extending top plate; a box like casing slidably supported on said top plate to complete the structure; means in said top plate for receiving and supporting a pencil in vertical position; means including provision for clamping an inserted pencil and holding it against movement relatively to the receiving means; a rotatable cutter supported by and below said top plate and having its axis inclined to the vertical; means for swinging said cutter toward and away from an inserted pencil; means for normally maintaining said cutter swung away from cutting position; 10 a crank supported in said upright; and gear connections between said crank, cutter, and pencil receiving means for rotating the cutter and pencil receiving means whenever the crank is actuated, and in such directions that the engaging surfaces of the cutter and pencil rotate in opposite directions.
7. A pencil sharpener including a frame comprising a base, an upright, and a horizontal extending top plate; a box like casing slidably supported on said top plate to complete the structure; said top plate having a counter bore in its under surface to receive a spur gear; a spur gear in said counter bore having a plurality of axially extending radially spaced segmental parts defining a pencil receiving space; a collar surrounding said segmental parts and having internal wedges movable in the spaces between said segmental parts; other complementary wedges in said spaces between said segmental parts movable 20 radially thereof by axial movement of said collar; a ring overlying the outer end of said segmental parts and secured to said spur gear by bolts passing axially through said segmental parts; springs about said bolts between said gear and lugs of 30 said collar tending to urge said collar away from said gear to normally hold said other wedges projected; and a cap overlying said collar and ring and being apertured to receive a pencil and serving as a finger rest to push said collar to release 40 a pencil.
8. A pencil sharpener including a frame comprising a base, an upright, and a horizontally extending top plate; a box like casing slidably supported on said top plate to complete the structure; means in said top plate for receiving and supporting a pencil in vertical position; said means including provision for clamping an inserted pencil and holding it against movement with respect to the receiving means; a sleeve 50 dependent from said top plate and having a radial arm for supporting a rotary cutter, a rotary cutter supported by said arm; manually operable means for swinging said cutter against a pencil; spring means for swinging the cutter away from a pencil; a crank; and gear means operable by said crank for simultaneously rotating the cutter and said pencil receiving means; manually operable means for swinging said arm and cutter against a pencil; and spring means for swinging said arm and cutter away from a pencil.
9. A pencil sharpener including a frame comprising a base, an upright, and a horizontally extending top plate; a box like casing slidably supported on said top plate to complete the structure; means in said top plate for receiving and supporting a pencil in vertical position; said last means including wedge means movable bodily in vertical planes inwardly and outwardly for clamping a pencil in said first means and holding it against movement with respect to the same; spring urged cooperating complementarily shaped wedge means for holding said first wedge means against a pencil; said last means being manually operable to release a pencil; a crank; and gear means operable by said crank for simultaneously rotating the cutter and said pencil receiving means.
10. A pencil sharpener comprising a frame, a casing slidably associated with said frame, pencil receiving and holding means in the top plate of said frame adapted to receive and hold a pencil in vertical position, an abutment against which the end of said pencil stops when inserted for sharpening, a rotatable cutter mounted to swing against and away from an inserted pencil and disposed with its axis at an angle to the pencil axis; manually operable means for swinging said cutter against the pencil; a crank, and gear means operable by said crank for simultaneously rotating the cutter and said first mentioned means.
11. A pencil sharpener including a frame comprising a base, an upright, and a horizontally extending top plate; a box like casing slidably supported on said top plate to complete the structure; said top plate having a counter bore in it to receive a spur gear; a spur gear in said counter bore and having a plurality of axially extending radially spaced segmental parts defining a pencil receiving space; a collar surrounding said segmental parts and having internal wedges movable in the spaces between said segmental parts; other complementary wedges in said spaces between said segmental parts movable radially thereof by axial movement of said collar; cooperating shouldered engagements between said segmental parts and said other wedges to limit movement of said other wedges towards the axis of said pencil receiving space and to prevent dislodgment of said other wedges from operative position; a ring overlying the outer ends of said segmental parts and secured to said spur gear by bolts passing axially through said segmental parts; springs about said bolts between said gear and lugs on said collar urging said collar away from said gear to normally hold said other wedges projected; a cap overlying said collar and ring adapted for receiving a pencil and serving as a finger rest to push the collar to release a pencil; a sleeve depending from the under side of the top plate and having a radial arm for supporting a cutter; a rotatable cutter mounted on said arm and extending towards said top plate; a crank; gear means operable by said crank for simultaneously rotating the cutter and said pencil receiving means; manually operable means for swinging said arm and cutter against a pencil; and spring means for swinging said arm and cutter away from a pencil.
12. In a pencil sharpener of the rotary cutter type, means for receiving a pencil to be sharpened, means mounting the cutter and supporting it for movement towards and away from an inserted pencil, means for moving said cutter against an inserted pencil, and adjustable stop means for limiting the extent of movement of said last mentioned means as it is actuated for holding the cutter against a pencil.
13. In a pencil sharpener of the rotatable type, means mounting the cutter for bodily movement towards and away from the pencil axis to vary the cutting effect of the cutter against an inserted pencil, stop means for limiting the movement of the cutter against a pencil, and means operable manually for adjusting said stop means to accommodate the cutter to pencils of varying sizes.
14. In a pencil sharpener, means for receiving and gripping a pencil during the sharpening

operation, a cutter movable towards and away from an inserted pencil, a lever for moving said cutter, a fixed stop for limiting movement of the cutter in a direction away from a pencil, adjustable stop means for limiting the movement of the cutter in a direction towards an inserted pencil, said latter means including a bell crank have one arm adapted to be engaged by the lever when swung in a direction to move the cutter towards a pencil, and manually operable means for shifting the bell crank about its pivot to change the point of contact between the short arm of the bell crank and said lever.

15. In a pencil sharpener of the box type, means for receiving and gripping a pencil to be sharpened with its point within the box, a cutting element within the box movable towards and away from an inserted pencil, a lever projecting through the box for moving said cutter towards and away from a pencil, and an adjustable stop means manually operable outwardly of the box for limiting the movement of the cutter by its lever towards and against a pencil to be sharpened. 5

MARTIN BERSTED.
